UNITED STATES PATENT OFFICE

FRANCIS J. STRAUB, OF NEW KENSINGTON, PENNSYLVANIA

CEILING SLAB SUPPORT

Application filed April 27, 1929. Serial No. 358,543.

My invention is an improvement in building construction and more particularly in the class of ceiling slabs of concrete or other similar material. It has in view to provide easy and convenient means for supporting a slab or other similar section of ceiling material below main supporting elements, as I-beams or the like, to provide a continuous enclosing ceiling surface.

Also, whereby the several slabs may be easily and quickly placed in position and connected with the flange or flanges of the supporting structural members, by means of movable elements mounted in the slab and adapted to be withdrawn and to engage the structural members.

In the class of fireproof construction, ceiling slabs or sections of suitable material, as concrete, tile, or the like, are usually pre-formed of any suitable aggregate of cementitious or refractory material, and are ordinarily reinforced by transverse metal rods or the like for strength, as is generally understood.

The present invention is capable of adaptation to any such ceiling element or unit, whether reinforced or not, for the purpose of securely supporting it, in the manner more fully hereinafter described.

Referring to the drawing showing certain preferred embodiments of the invention:

Fig. 1 is a transverse sectional view, partly broken away, showing a continuous series of ceiling slabs supported from upper main structural members, according to my invention;

Fig. 2 is a plan view, partly broken away, of one such unit, with the supporting elements extended at one end and pushed in at the other;

Fig. 3 is a sectional view similar to Fig. 1, showing a modified construction of the slab members;

Fig. 4 is a plan view showing a further modification in the construction of the movable supporting element;

Fig. 5 is a sectional view through one end of a slab, showing an inserted bearing tube or ferrule.

The ceiling slab 2 of concrete, tile, or any

equivalent construction is usually made in rectangular sections for the covering of the ceiling area underneath the main floor beams 3 of suitable structural shape, and preferably of I-beam form.

Beams 3 extend across between walls, columns, or other main supports, and the ceiling slabs 2 are adapted to be connected therewith by the means hereinafter illustrated and described, comprising one or more movable bolts or similar devices, capable of being withdrawn edgewise from the slab, for supporting engagement upon the beam flanges 4.

In the construction shown I utilize nails or spikes 5, preferably having the usual terminal heads, and insertible edgewise in pre-formed sockets or openings 6, located at suitable positions inwardly of the edge of the slab 2, at its opposite ends.

The sockets 6 may be pre-formed in the manufacture of the slabs, and may be slightly inclined as in Figs. 1 and 3, or may be on the same general level or parallel with the upper and lower faces of the slab, as preferred.

The inner end portions of the slab are preferably offset as shown, providing the lower extensions 7, so as to substantially abut against the corresponding extended edge portion of the next adjacent slab, for closure.

The inwardly off-set ends 8 of the slab provide ample space surrounding the lower flanges 4 of the beam to permit of upward placement of the slabs in application or erection, while at the same time providing the intervening cavity for filling with grouting 9 of any suitable material, as in Fig. 3.

Such figure also shows, at 10, inwardly extending grooves or channels along the inner upper face of the slab, providing a secure interlocking connection between the grouting and the slab at each side of the flanges, so that, should the principal supporting elements become rusted or broken, the slab will be still maintained in position against falling.

In Fig. 4, I show a modified construction in which a U-shaped support, similar to a staple, is inserted by its endmost lugs 11 within suitable receiving openings 6 in the

slab, and is provided with a transverse outer bar portion 12, adapted to rest upon the beam flange when withdrawn, as indicated in dotted lines.

In Fig. 5, I show a further modification in which the slab is provided with a lining or ferrule 13 of tubular form, inserted in a suitable cavity, either in manufacturing the slab or in a later formed hole. By such construction the spike or bolt 5 is provided with a mounting support providing for easy in-and-out sliding movement of the spike.

From the foregoing the construction and operation of the invention will be readily understood. Previous to elevating the particular slab to its position the spikes will be thrust inwardly, their heads in such position passing freely with clearance upwardly beyond the flange 4, and when thus elevated the spikes are then drawn outwardly as in Fig. 1, resting upon the inner portions of the flange at opposite sides.

When thus supported the entire weight of the slab will rest by such spike or bolt engagement, and the several slabs forming the entire ceiling are thus located. By properly positioning the openings 6, the slabs will all rest with their lower surfaces in alinement on a common plane.

Thereafter, upon filling the intervening space with the grouting 9, the entire construction is solidly incorporated, further strengthening and stabilizing the ceiling structure and at the same time fixedly engaging the spike heads against return movement, due to vibration or other causes.

It will be understood that any desired number of the movable supporting elements may be utilized and that they may be of any suitable or desired form, and located at any desired angle or position. The construction facilitates and reduces the time of erection work, and is extremely simple, cheap, and continuously serviceable.

Various changes or modifications may be made in the detail construction of the parts or in their arrangement or location, or otherwise by the skilled mechanic. It will also be understood that the invention is applicable to use in connection with various flanged structural members, or in connection with any other form of support providing a bearing for the inner ends of the bolts, but all such changes are to be understood as within the scope of the following claims.

What I claim is:

1. A ceiling slab having at opposite ends inwardly extending closed bottom sockets provided with a tubular bearing and a supporting bolt movably mounted in each socket provided with a projecting supporting terminal.

2. In combination with a pair of spaced

apart structural beams having a lower lateral flange on a common level, a ceiling slab located between the beams having the lower portion of its opposite ends adjacent the beam projecting inwardly underneath its flange and its upper portion projecting thereabove, each of such end portions having an inwardly extending closed end socket, and a freely movable independent supporting bolt in each of said sockets having a projecting terminal resting on the beam flange.

3. In combination with a vertical I-beam, a pair of ceiling slabs located on a common plane with their adjacent ends terminating at each side of the beam each having a vertically disposed end face spaced beyond and above the flanges of the beam and provided with an inwardly extending closed end socket and a lower sloping extension projecting underneath the flange providing a grout containing cavity, and a freely movable short supporting bolt in each of said sockets having a projecting terminal resting on each opposite beam flange.

4. In combination with a vertical I-beam, a pair of ceiling slabs located on a common plane with their adjacent ends terminating at each side of the beam each having a vertically disposed end face spaced beyond and above the flanges of the beam and provided with an inwardly extending closed end socket, an inner upwardly extending edge portion on each slab providing a grout-engaging off-set recess at each side of the beam, a lower sloping extension projecting underneath the flange providing with said recess a grout containing cavity, and a freely movable independent supporting bolt in each of said sockets having a projecting terminal resting on each opposite beam flange.

5. In combination with a plurality of spaced apart I-beams located on a common plane, a series of ceiling slabs having plane lower surfaces each provided with backwardly recessed lower edge portions adapted to extend below each lower beam flange towards the edge portion of an adjacent slab and upwardly extending end faces providing a gap closing filling space around the flanges, the opposite end portions of each slab having closed bottom sockets provided with inwardly and outwardly movable supporting bolts adapted to be adjusted independently of the bolts at the opposite end of the slab in supporting engagement or disengagement with the adjacent flange of the beam.

6. In combination with a plurality of spaced apart I-beams located on a common plane, a series of ceiling slabs having plane lower surfaces each provided with backwardly recessed lower edge portions adapted to extend below each lower beam flange towards the edge portion of an adjacent slab

and upwardly extending end faces providing a gap closing filling space around the flanges, the opposite end portions of each slab having closed bottom sockets provided
5 with inwardly and outwardly movable supporting bolts adapted to be adjusted independently of the bolts at the opposite end of the slab in supporting engagement or disengagement with the adjacent flange of the
10 beam, and a filling of grouting in the space between the adjacent slab terminals and around the beam flanges and imbedding the projecting portions of the bolts.

In testimony whereof I hereunto affix my
15 signature.

FRANCIS J. STRAUB.
